STAYBOLT ASSEMBLAGE

John Rogers Flannery, Pittsburgh, Pa., assignor
to Flannery Bolt Company, Bridgeville, Pa., a
corporation of Delaware

Application August 15, 1935, Serial No. 36,315

4 Claims. (Cl. 85—1.5)

This invention relates to staybolt assemblies, and more particularly to staybolts of the character provided with an internal longitudinally extending passage or tell-tale hole.

Staybolts have heretofore been constructed having a tell-tale hole therein, the arrangement being such that one end of the staybolt is rigidly attached to one of the two boiler sheets, while the other end of the bolt has a universal connection with the other boiler sheet. Such an arrangement permits of a considerable relative movement between the two boiler sheets arising by reason of the expansion or contraction of the sheets or from other causes. It is not, however, entirely flexible by reason of the fact that one end of the bolt is rigidly anchored to one of the sheets. The tell-tale hole is provided in the bolt either for the purpose of indicating when the bolt is cracked or broken by enabling water to escape from the boiler through the ruptured bolt into the tell-tale hole, or the tell-tale hole is provided for the reception of some kind of an indicating or testing means adapted to be projected into the hole for determining a defect in the bolt.

It has been recognized also that a greater flexibility can be secured in a staybolt by having a universal connection between the bolt and the boiler sheets at each end of the bolt rather than at one end only. Such constructions, however, have been such that they would not permit of the provision of a tell-tale opening or passage for the accommodation of a testing tool so that the inspection of such bolts is quite difficult.

According to the present invention there is provided a staybolt assembly in which the main portion of the staybolt has a universal mounting at each end and wherein the tell-tale opening or passage for the reception of a testing implement is accessible from the outside of the boiler and extends throughout the greater portion of the length of the staybolt assembly, the assembly, however, being fluid-tight whereby it will not leak except in the event of the bolt becoming defective.

The invention may be readily understood by reference to the accompanying drawings which illustrate certain embodiments of my invention and in which:

Figure 1 is a longitudinal sectional view of a staybolt assembly embodying my invention;

Figure 2 is a similar view showing a slightly modified arrangement; and

Figure 3 is a similar view showing still another modification.

Referring first to Fig. 1 of the drawings, 2

designates one of the two boiler sheets to be connected by the staybolt, and 3 designates the other boiler sheet. The sheet 2 is that sheet which forms the walls of the fire box and is termed the "fire sheet", and the other sheet 3 is commonly designated the "wrapper sheet". The space between the two sheets, of course, is the boiler space within which is water or steam. The staybolt assembly comprises a main bolt member 4 and a connecting member 5. The main bolt member 4 is provided on one end with a substantially spherical head 6. In the particular construction shown in Fig. 1 the head 6 is shown as having a seat in a sleeve 7 which is welded or otherwise secured to the sheet 3, as indicated at 8. The head 6 therefore cooperates with the sleeve 7 as a coupling at the respective end of the main bolt member 4 for providing a universal connection with the wrapper sheet 3. The end of the sleeve is closed against the escape of fluids by a screw cap 9. This particular seating arrangement is a conventional arrangement for flexible staybolts. The spherical head 6 has a universal movement in the sleeve member 7, being free to rock in any direction and being free to lift away from the seat if conditions cause such movement. The opposite end of the bolt is shown as being provided with a hemispherical head portion 10 and as having a forwardly extending projection 11 thereon extending beyond the head, this portion 11 being threaded as shown. The bolt is provided with a tell-tale hole 12 which extends throughout the major portion of the length of the bolt, being open at one end and preferably being closed at the end 6. The reason for the closure in the head 6 is to prevent fluid which may leak around the head 6 into the space within the sleeve 7 from escaping back through the tell-tale opening. The connector member 5 in the particular embodiment shown is screwed into the boiler plate 2 and has a head portion 13 which is riveted over. The inner portion 14 of the member 5 is of enlarged diameter and is externally threaded. Fitted over this portion 14 is a sleeve member 15, the members 14 and 15 together forming a substantially hollow spherical chamber 16 in which the head portion 10 of the bolt is received, this chamber also receiving the threaded projection 11. The connector member 5 thus provides a universal seating for the head portion 10 of the bolt. There is a longitudinally extending passageway 17 in the member 5 which registers with the passage 12 in the main bolt member 4, forming in effect a continuation of 55

the passage 12 to the exterior of the bolt. Inasmuch as fluid may leak past the grounded head 10, a seal is provided between the bolt member 4 and the connector member 5 to prevent the fluids of the boiler from escaping through the passage 17. In the arrangement shown in Fig. 1 this seal comprises a corrugated flexible diaphragm or gasket 18 having its periphery clamped between the end of the portion 14 and an internal shoulder 19 inside the member 15. This diaphragm has a central opening through which the portion 11 of the bolt passes, and a nut 20 on the portion 11 clamps the edges of this central opening against a small shoulder 21 on the head 10 portion of the bolt.

An effective seal is thus provided against the escape of fluids in the connection between the member 4 and the member 5. In the embodiment shown, the fluid can not escape through the opposite end of the passage 12 because of the fact that this passage terminates within the head 6 and therefore any fluid which accumulates in the sleeve 7 around the head 6 cannot escape through the passage 14.

25 In order to prevent the flanged coupling member 15 from loosening under vibration or motion of the bolt, the parts 14 and 15 may be welded after the assembly has been made, as indicated at 22. The nut 20 may also be welded at 23 to the portion 11 for the same purpose. The parts 4 and 5 with the sealing means provide, in effect, a single articulated unit having a continuous tell-tale hole extending from one end of the unit throughout the greater portion of the length of the unit. As stated above, the hole itself may be used to indicate a leakage in the boiler inasmuch as a break in the bolt or a leak in the gasket will permit fluid to escape into the passage 12 and its presence can be detected at the open end of the hole. Likewise, the hole can accommodate various electrical testing devices adapted for insertion in a hole to determine either the condition of the bolt or the condition of the hole.

45 The construction shown in Fig. 2 merely shows another type of assembly embodying my invention. In this figure the main part of the bolt, designated 25, is shown as having the head 26 screwed thereon. The tell-tale hole 27 extends throughout the length of the bolt and is closed at one end by a plug 28.

It will be noted that in the arrangement shown in Fig. 1 the opening in the wrapper sheet is of sufficient diameter to enable the bolt assembly to be inserted through the wrapper sheet of the boiler. In the arrangement shown in Fig. 2 this hole 29 is relatively smaller and the assembly is inserted from the fire sheet side of the boiler. The sleeve which provides a seat for the head 26 is designated 30 and it is closed by a cap 31. At the opposite end of the bolt the connector member 32 has a relatively large head portion 33 adapted to span the hole 34 in the fire sheet, the head of this connector overhanging the outer edge of the hole. The bolt member 25 is provided with a rounded or hemi-spherical head portion 35 which is received in a cavity 36 formed within a flanged nut 37 and the end portion 38 of the connecting member 32, the flange on the nut 37 being rounded to the contour of the head 35. The gasket or sealing diaphragm designated 39 is clamped in the manner above described in connection with Fig. 1 and is shown as being laminated.

75 The construction shown in Fig. 3 is substan-

tially similar to that previously described. There is a main bolt member 40 and a connector member 41. The main bolt 40 in this case is shown as having a spherical head 42 which seats directly in a suitably rounded cavity in the wrapper sheet 5 43. There is a cap 44 welded directly to the wrapper sheet closing this end of the bolt to seal the latter against the escape of fluids. The opposite end of the bolt member is provided with a substantially spherical head 45. The coupling member 41 has a head portion 46 which covers the opening 47 in the fire sheet, this opening being of sufficient diameter to permit the insertion of the assembly from the fire sheet end of the boiler. The connector member 41 has an inner end portion 48 which is exteriorly threaded to receive a coupling nut 49. The inner surfaces of the portion 48 and the nut 49 provide a substantially spherical cavity conforming to the contour of the head 45, thereby providing a universal bearing for the head portion 45 of the bolt 40. The bolt 40 is provided with a tell-tale hole 50. The connecting member 41 is provided with a central passage 51 which has a restricted neck 52 and an outwardly flared portion 53 which is internally threaded. The flexible diaphragm or gasket in this case is shown as comprising a corrugated tubular member 54 formed of a flexible metal. The outer end of this tube is flared outwardly and clamped to the member 41 by a nut 30 55 screwed into the socket 53, the nut 55 having a central opening 56.

The opposite end of the tubular diaphragm 54 is flared outwardly and is clamped in place by means of a nut 57 screwed into an internal threaded socket 58 in the head 45 of the bolt.

The modifications shown in Figs. 2 and 3, like the construction shown in Fig. 1, provide in effect an articulated bolt assembly comprising the main portion of the bolt and the connector member, the assembly having a tell-tale hole extending throughout the greater portion of its length and open at one side of the boiler either for inspection or for the reception of a testing or indicating implement.

45 It will be noted in all of the various arrangements herein specifically described that the flexible gasket or diaphragm, which is preferably made in each case of a flexible metal, such for instance, as phosphor bronze, connects to the end of the bolt at a point close to the center of rotation of the head in its seat. The advantage of this is that the diaphragm is subjected to a minimum amount of flexing on a relative movement between the main bolt member and the connecting member.

It will also be noted that the flexible joint is located between the boiler plates. The overall length of the unit is thereby reduced and there is practically nothing at the end of the assembly 60 projecting into the fire box. In commercial practice the tell-tale hole is normally kept open and leakage is detected directly by the observation of the escape of fluid from the hole. However, various devices have been proposed for insertion in 65 the tell-tale hole to function in connection with electric indicating devices to show when the bolt is ruptured or broken.

The term "tell-tale hole" as herein used is intended to indicate this passage when it is left 70 open in accordance with the general commercial practice, or some detecting implement is inserted therein.

While I have shown and described certain specific embodiments of my invention it will be 75

understood that this is merely by way of illustration. There are various commercially known ways of providing a seat between the staybolt and the wrapper sheet, and the present invention 5 contemplates that the universal mounting in the wrapper sheet shall include such various types of mountings. It will also be understood that the invention is applicable to that type of staybolt in which provision is made for inspecting the 10 tell-tale opening from the wrapper sheet end of the bolt rather than from the fire sheet end, such arrangements being well-known in the art and forming no part of the present invention.

Various other changes and modifications may 15 be made in the construction and arrangement of parts within the contemplation of my invention and under the scope of the following claims.

I claim:

1. The combination with spaced plates, of a 20 staybolt unit flexibly connecting the plates, comprising two members swivelly connected between the plates, one of said members having a swivel connection with one of said plates, the other member being connected with the other plate, 25 said unit having a continuous passageway extending the length of one member and throughout the greater portion of the length of the other member so as to vent said continuous passageway through one end only of said unit, the swivel connection being provided with a flexible diaphragm 30 forming a fluid-tight seal between the members to prevent boiler fluid from entering the passageway.

2. In a flexible staybolt, the combination of a 35 main bolt member having a coupling at one end for providing a universal connection with a boiler sheet, and a connector member jointed to the other end of said main bolt member by a universal coupling, there being a passageway through 40 said connector member and a tell tale hole in the main bolt member in communication with said passageway and extending to adjacent the first mentioned sheet and closed at said end of the bolt member, said connector member being provided with means for connecting the bolt to a 45 boiler sheet spaced from the first mentioned sheet, said last mentioned universal coupling being disposed between said boiler sheets and comprising

a head portion on the end of one of said members, a sleeve threaded on the adjacent end of the other member and cooperating therewith to provide a chamber receiving said head portion and a universal seating therefor, and a flexible 5 seal between said members for excluding boiler fluid from said passageway.

3. The combination with spaced plates, of a staybolt member connected to one of said plates and projecting into the boiler space, a main bolt member jointed to the inner end of the first mentioned member by a universal coupling comprising a head portion on the end of the main bolt member and a sleeve threaded on the adjacent end of the first mentioned member providing a 10 universal seating for said head, said main bolt member having a coupling at its other end for providing a universal connection with the other boiler plate, and a flexible seal between said members at the joint therebetween, there being a passageway through the first mentioned member and a tell tale hole in the main bolt member in communication with said passageway and extending to the second mentioned coupling and closed at 15 said end of the bolt member.

4. A flexible staybolt assembly comprising an articulated staybolt unit, and a coupling at one end of the unit for providing a universal connection with one of two spaced plates, said unit including a main bolt member having said coupling 20 at one end, there being a tell tale hole in said member opening through the other end thereof and extending to said coupling and closed at said end of the member, a connector member jointed to said main bolt member by a coupling comprising a head portion on the main bolt member, a recessed portion on the connector member and a sleeve threaded thereon and cooperating therewith to provide a chamber receiving said head portion and a universal seating therefor, there 25 being a passageway through said connector member in communication with said tell tale hole, and a flexible seal at said joint between said members for excluding the boiler fluid from said passageway, said connector member being provided with 30 means for connecting the unit to the other plate.

JOHN ROGERS FLANNERY.
